UNITED STATES PATENT OFFICE.

BYRON B. BROCKWAY, OF CLEVELAND, OHIO, ASSIGNOR TO THE DEAN ELECTRIC COMPANY, OF ELYRIA, OHIO, A CORPORATION OF OHIO.

TELEPHONE CALL-REGISTER.

No. 896,081.

Specification of Letters Patent.

Patented Aug. 18, 1908.

Application filed March 30, 1906. Serial No. 308,955.

To all whom it may concern:

Be it known that I, BYRON B. BROCKWAY, a citizen of the United States, residing at Cleveland, in the county of Cuyahoga and 5 State of Ohio, have invented certain new and useful Improvements in Telephone Call-Registers, of which the following is a specification, reference being had therein to the accompanying drawing.

10 My invention relates to call registers for telephone systems, and has for its object the production of a form of register which shall be efficient, simple in itself, and also very simple in its mode of mounting.

15 My register is of that type which is located at the subscriber's station, this being for many reasons the most desirable type of register to be used in systems where the charges are based upon the number of messages trans-

20 mitted from any station. In such case, if the registers are located at the central office, or if the message-count is based upon tickets made out by the operators, it is not only very difficult to prevent losses, but it is more

25 difficult to satisfy the subscribers that false charges are not made against them. By permitting the subscriber to register his own call, in such fashion that he can see and count the number of messages he has sent,

30 at all times, three important ends are attained. The first is to satisfy the subscriber; the second is to relieve the operator of an undesirable addition to her work, and the third is to assure greater accuracy in the final rec-

35 ords, with attendant saving of many calls which would otherwise be lost. It is true that with this system inspectors must be sent out to read the meters at stated intervals, but this has always been done in other

40 public service systems, such as those supplying gas and electric light, and the expense of the inspectors has never been found prohibitive to my knowledge.

Several difficulties have heretofore existed 45 in respect to subscribers' registers. They have been subject to being tampered with, they have not been susceptible of application to all types of instruments, and they have not always been "fool-proof", which is

50 a *sine qua non*. Anything placed at the subscriber's station must be capable of operating only as it is intended to perform its function.

If any possible means exists for misoperating, or mishandling a piece of apparatus, the subscriber or some of his family will find it. Practi-

60 cally the only act which the average person should be asked to perform in operating any apparatus is to push a button or lever. The intelligence of the untrained extends no further.

65 It has been proposed to attach registers to different portions of the telephone set, and toll boxes have been so attached, the idea being that a special sound produced in the dropping of a coin will produce sonorous vibrations in the frame or casing, thence in the transmitter, and thence by translation over the line, in the operator's receiver. Such devices have not always worked well, for one reason because it is now common to insulate 70 the diaphragm of the transmitter with a soft rubber band, which acts as a sound insulator as well as electrically. It has also been proposed to attach some portions of the toll apparatus or the like to the transmitter itself, 75 but the attachment has always been unsatisfactory because being detachable of necessity, it could be taken off by other than authorized persons, and being fixed to other members than the transmitter, it necessarily 80 limits the movement of the latter.

85 My register is designed to obviate the objections to which I have referred, and many others. It comprises as its essential element a lever-operated Veeder cyclometer register attached within the shell of the transmitter, and provided with means to produce a distinctive sound each time it is operated. The figures of the register are readable through an opening in the front plate, and the entire 90 instrument may be so sealed up if required, as to remove any possibility of tampering.

95 In the drawings which form a part of this application Figure 1 is a sectional view taken by breaking away the left side of the transmitter and the inclosing case of the register sufficiently to show the interior of the latter. Fig. 2 is a front view of the shell of the transmitter with the register secured in place, but the front plate and transmitter parts removed. Fig. 3 is a face view of the transmitter with the register, complete.

100 Referring to the drawings, 1 represents a transmitter front and 2 the mouthpiece thereof, 3 the diaphragm and 4 the carbon button, all of the ordinary or any desired type.

105 5 represents an inclosing shell adapted to fit the front-plate 1 and carrying or having formed integral with it an extension shell 6 110

for the register. This extension shell has a removable front-plate 7 with an aperture 8, through which the numbers in the register 9 may be seen. This register, as I have stated, 5 is of the Veeder cyclometer type, and is secured to the back of the inclosing shell 6 by a screw 10.

Secured to the shaft 11 of the register is an 10 operating lever 12 provided with a thumb piece 13 projecting through a slot 14 in the bottom of the inclosing shell 6. The upper end of this operating lever is provided with a stud or pin 15 adapted to engage with and operate the reed 16, of peculiar formation, 15 mounted upon a post 17, secured to the back of the inclosing shell 6. The forward end of this reed, or that engaged by the pin, has a depending ear or tongue 18 which is bent so as to form a pair of cam-faces for the pin to 20 ride upon. The operating lever has a coiled spring within the cyclometer, not shown in the present drawings, which returns it to normal position, as shown in Fig. 1, each time it is actuated. The pin 15 of the lever 25 rides up over the tongue 18 in its forward movement and rides under the tongue, pressing it upward in its backward movement. At the extremity of each movement the pin slips off the tongue, and by suddenly releasing 30 it while under tension, causes it to vibrate.

When a subscriber calls central, before he is connected with the line wanted, he is told to register, and when his thumb-piece 13 is 35 depressed the pin 15 rides over the tongue 18, passes the reed, and the latter snaps up with a sound which is communicated to the back of the diaphragm through the air and thence to the carbon button. At this time 40 the lever is at the end of its forward movement, and when returned by the spring the pin again engages the tongue upon the under side and raises it up until the lever gets to the end of its backward movement, when it is 45 again released and allowed to drop, producing another sound also communicated to the diaphragm, and the resistance button. In making the forward movement the meter is operated and a new number registered on the 50 right hand disk. At stated periods, readings are taken from all the registers at the substations, and the amount of chargeable business thus determined.

It will be observed that by this arrangement I avoid any obstruction in front of the transmitter, or on its supporting parts. I cause a vibration in the inclosed air back of the diaphragm, and I render it possible to fit any instrument, as it is only necessary to 55 change the shell, and the number of sizes in standard shells is now very limited.

Having thus described my invention, what I claim and desire to secure by Letters Patent is:

65 1. A call register for a telephone system

carried in and secured to a transmitter shell so as to communicate directly with the back of the diaphragm, and a member permanently secured to such register extending through such shell, adapted to operate such 70 register, substantially as described.

2. A call register for transmitters comprising a registering device and a sounding device carried by and within the transmitter shell, said sounding device adapted to communicate its vibrations directly to the diaphragm, and a member permanently secured to such register extending through such shell, adapted to operate such register, substantially as described. 75

3. A call register for telephone systems, comprising a registering device and a sounding device operated simultaneously therewith, said devices carried directly in the transmitter and said sounding device adapted to direct its vibrations or sounds to the back of the diaphragm, and a member permanently secured to such register extending through such shell, adapted to operate such register, substantially as described. 80

4. In a device of the class described, the combination with the transmitter shell, of an extension shell carried thereby, registering means and sounding means within said extension shell, and means for operating both simultaneously, said sounding device adapted to communicate its vibrations directly to the back of the diaphragm; and a lever permanently connected to such register extending through such shell, adapted to operate such 95 register, substantially as described.

5. In a device of the class described, the combination with a transmitter having a front plate and a diaphragm bearing thereagainst, of an inclosing shell mounted on the front plate, a registering device carried within and behind said front plate so as to be visible to the user of the telephone, means for operating said registering device, a sounding device, said register-operating means adapted also to operate said sounding device so that at the same time the sound is communicated to the diaphragm from the sounding device, the register is operated to record the call, and a lever permanently connected to such register extending through such shell, adapted to operate such register, substantially as described. 105

6. In a device of the class described, the combination with a transmitter shell, of an extension shell carried thereby, registering means secured within said extension shell, a sounding device also secured within the extension shell, an operating lever permanently connected to such register extending through such shell and adapted to simultaneously operate the sounding device and the registering device, and a front plate for the shell, having a sight opening, substantially as described. 115

7. In a call register, the combination with 120

a transmitter shell, a sounding reed mounted therein, a registering device also mounted therein, and a lever permanently connected to such register, extending through such shell, for operating said registering device, and an extension on said operating means for vibrating the sounding reed.

In testimony whereof I affix my signature in presence of two witnesses.

BYRON B. BROCKWAY.
